GEORGE A. JOHNSON, OF CHICAGO, ILLINOIS, ASSIGNOR TO WILLIAM H. MINER, OF CHAZY, NEW YORK.

DRAFT-ARM FOR RAILWAY-CARS.

1,228,563.

Specification of Letters Patent.

Patented June 5, 1917.

Application filed October 9, 1914. Serial No. 865,789.

To all whom it may concern:

Be it known that I, GEORGE A. JOHNSON, a citizen of the United States, residing at Chicago, in the county of Cook and State of Illinois, have invented a certain new and useful Improvement in Draft-Arms for Railway-Cars, of which the following is a full, clear, concise, and exact description, reference being had to the accompanying drawings, forming a part of this specification.

My invention relates to improvements in draft arms for railway cars.

The object of my invention is to provide a draft arm of strong construction, suitable for attachment to the underframe of a railroad car.

In the drawings forming a part of this specification, Figure 1 is a vertical longitudinal section taken on line 1—1 of Fig. 2 of a draft arm embodying my invention. Fig. 2 is a plan view partly in horizontal section on line 2—2 of Fig. 1. Fig. 3 is a cross section on line 3—3 of Fig. 1.

Referring to the drawings, the numerals 4—4 indicate center sills of a car underframe terminating rearwardly of the end sill 5. A buffer block 6 is suitably secured to the end sill and the structure is provided with a draw bar carry arm 7 of usual type. The draft arm 8 comprising my invention consists of an inverted U-shaped member 9, preferably a casting having the side plates 10—10 thereof suitably spaced apart to receive a draft rigging between them, the said plates being connected at their upper ends by the preferably integral transverse member 11. The side plates 11—11 are each provided with a suitable longitudinally extending groove 12, each adapted to receive a limb 13 of the horizontally arranged draft yoke 14. At its forward end the draft arm 8 is provided with a preferably upturned flange 15, which is suitably secured to the end sill 5 preferably by the rivets 16. Each side member 10 of the draft arm 8 at its rearward portion adjoins an inner face 17 of one of the center sills 4, said members being suitably secured to the center sills, preferably by the rivets 18—18.

The principal embodiment of my invention illustrated by the drawings is one adapted to receive a draft gear of the tandem type, the draft arm being provided with upper and lower front stop members

19 and 20 respectively, upper and lower intermediate stops 21 and 22 respectively, forming the front intermediate stop shoulders 23—23 and the rear intermediate stop shoulders 24—24. The same is also provided with upper and lower rear stop shoulders 25—25. The upper stop shoulders are preferably formed by suitable convolutions in the upper member 9 of the draft arm 8, the metal forming said member being in preferable construction of substantially uniform thickness throughout. Forward of the lower front stop shoulder 20 the draft arm 8 is provided with a preferably integral lower transverse connecting member 26 forming with the side members 10 and the upper member 9 a longitudinally opening pocket to receive the draw bar 27. In preferable construction, the lower front stop shoulder 20 is formed by an integral downturned flange at the rear end of the member 26. The front draft gear pocket 28 of the draft arm is adapted to receive suitable compression resisting members, preferably the outer spring 29 and the inner spring 30 nested therein. The rear draft gear pocket 31 within the draft member 8 is similarly adapted to receive suitable compression resisting members, preferably the outer spring 32 and the inner spring 33 nested therein. The lower openings 34—34 of the draft gear pockets 28 and 31, through which the draft gear is adapted to be received from below into the draft arm, are each provided with suitable closing means adapted to support the draft gear therein comprising preferably the plate 35 received through transverse slots 36—36 in the lower portion of the side members 10 of the draft arm 8, the said plates being provided at one end with a flange or head 37, and at the other end with a cotter 39 or other suitable means to prevent the accidental displacements thereof. Near their free ends, the limbs 13—13 of the draft yoke 14 are each provided with a transverse slot 40 for the passage of a coupler key 41 which is received within the draw bar and passes at its ends through suitable longitudinally extended transverse slots 43—43 in the side members 10—10 of the draft arm 8. The limbs of the draft yoke 14 are provided near their forward ends and rearwardly of the key slots therein with inwardly projecting shoulders 45—45, which in normal position of the parts of the draft rigging regis-

2

ter substantially with the front stop members 19 and 20. Intermediate its ends the yoke 14 is provided with a transverse connecting thimble 46, the front face 47 of which in normal position of the parts of the draft rigging substantially registers with the front intermediate stop shoulders 23—23 of the intermediate stops 21 and the rear face 48 of which substantially registers with the rear intermediate stop shoulders 24—24 of the intermediate stop members 21. The rear connecting member 49 of the draft yoke is received within the forwardly opening pocket 50, rearwardly 15 of the rear draft gear pocket 31, the said pocket 50 being preferably formed by convolutions in the member 9 of the draft arm 8, which in preferable construction terminates at the lower edge of the draft arm 8 at 20 the point indicated by the numeral 51 in Fig. 1 of the drawings, the same forming in preferable construction the rear stop shoulders 25. In normal position of the parts of the draft rigging the front face 52 of the 25 rear connecting member 49 of the draft yoke substantially registers with the faces 25 of the rear stop members. On forward movement of the draw bar the coupler key 41 slides forwardly in the slots 43—43 in the 30 draft arm, the forward movement of the yoke compressing the springs in the front draft gear pocket 28 between the front stop shoulders and the forwardly moving intermediate connecting thimble 46 of the draft 35 yoke. Similarly, the springs in the rear draft gear pocket 31 are on forward movement of the draw bar compressed between the rear intermediate stop shoulders 24 and the forwardly moving rear connecting member 49 of the draft yoke. On rearward movement of the draw bar, the springs in the 40 front spring pocket 28 are compressed against the front intermediate stop shoulders 23 by the rearwardly moving draw bar 45 and the inturned shoulders 45 of the draft yoke, while the springs in the rear spring

pocket 31 are compressed against the rear stop shoulders 25 by the rearwardly moving intermediate connecting thimble 46 of the draft yoke. The rear connecting member 49 of the draft yoke in rearward movement of the draw bar moves rearwardly in the pocket 50, extreme rearward movement being limited by the engagement of the rear member 49 of the draft yoke against the plate 55 forming the rear wall of the pocket 50.

I claim:—

1. A draft arm for railway car draft riggings comprising a hollow, box-like casting arranged to receive a horizontal yoke and having side and top walls, said casting being provided with a rear wall having a horizontal convolution therein adapted to receive the rear end of a yoke and accommodate its inward movement under buff, the side walls 65 of said casting being extended rearwardly beyond said convolution.

2. In a draft rigging, a hollow, box-like casting having stop shoulders, said casting being formed at its outer end with integral 70 upper and lower horizontal walls and vertical side walls, to thereby form a pocket adapted to receive the inner end of a draw-bar, said upper and lower horizontal walls being in line with the front stops. 75

3. As an article of manufacture, a draft arm for railway draft riggings, said draft arm comprising a box-like casting of substantially uniform thickness throughout, said casting being provided with longitudinally arranged convolutions on the sides thereof adapted to accommodate a horizontal yoke, said casting being provided also with integral transverse upper and lower convolutions approximately at the center 80 thereof, said transverse convolutions forming intermediate stops. 85

GEORGE A. JOHNSON.
